UNITED STATES PATENT OFFICE.

CHARLES C. THOMPSON, OF SAN DIEGO, CALIFORNIA.

DESIGN FOR A SPOON.

SPECIFICATION forming part of Design No. 23,310, dated May 29, 1894.

Application filed April 21, 1894. Serial No. 508,526. Term of patent 3½ years.

To all whom it may concern:

Be it known that I, CHARLES C. THOMPSON, a citizen of the United States, residing at San Diego, in the State of California, have invented a new and original Design for Spoons, of which the following is a specification, reference being had to the accompanying drawing, forming a part hereof, and in which the figure is a plan view.

- 10 The leading feature of my design for spoons consists in a land and sea view picture, within the bowl, which embodies the representation of a village in the foreground, hills back of the village and with the sun rising over the hills, a body of water to the right of the picture, and a lighthouse standing on a promontory at the extreme right hand end; the handle having its outer part enlarged and ornamented with a fanciful border of grape leaves,
- 15 within which is a picture of a mission building with a palm tree at the right hand end of the handle and standing across the length of the same; a panel between the widened end of the handle and the shank thereof; a bell
- 20 suspended from the panel, and a representation of a crown at the point where the tapered shank of the handle is joined to the bowl.

In the drawing, A represents the handle and B the bowl of the spoon. The handle is 30 made wider than the shank C which connects the same to the bowl, and this shank is slightly tapered and rounded from the wide flat end A to the bowl B, as shown. Within the bowl

is a picture of a village on the land at the left hand side, with hills in the back ground, and 35 the sun rising over the hills. On the right of the village is the representation of a body of water, with ships sailing thereon, and at the extreme right of the picture is a promontory, on which stands a lighthouse.

40 The end A of the handle is slightly oval, and provided with a fanciful border of grape leaves b, which extends around three sides of the wide part A and joins with or merges into a transverse panel D, from which is hung or 45 suspended the representation of a bell E. Within the border b and the panel D, is the representation of a mission building, and in the foreground, shrubbery or tropical plants are represented, with a palm tree at the right 50 hand end of the picture. At the outer end of the handle is provided the figure of a bear, F, which is represented standing across the handle, at right angles to its longitudinal axis. A representation of a crown, G, is provided 55 on the tapered shank of the spoon at the point where the shank is joined to the bowl.

Having thus described and explained the nature of my invention, what I claim as new is—

60 The design for a spoon substantially such as herein shown and described.

CHARLES C. THOMPSON.
